UNITED STATES PATENT OFFICE

WILLIAM J. SULLIVAN, OF CHICAGO, ILLINOIS, ASSIGNOR TO AMERICAN EQUIPMENT COMPANY, OF CHICAGO, ILLINOIS, A CORPORATION OF OHIO

DUMPING FORK

Application filed August 1, 1930. Serial No. 472,337.

My present invention relates to brick handling devices, and more particularly to an improved brick lifting and dumping fork.

Heretofore, when utilizing dumping forks with rigid fingers, it has been necessary to dump or tilt the fork a considerable distance above the wagon or other receptacle adapted to receive the brick. This resulted in a considerable impact or jarring of the wagon or 10 other receptacle, as well as in the breakage and misalignment of the bricks so dumped.

Furthermore, with the prior type of brick fork with rigid fingers, only a portion of the brick would drop therefrom when the fork 15 was dumped, it being necessary to knock or remove the balance of said bricks from said fork by hand.

An important object of the present invention, therefore, is the provision of a dumping 20 device which may be dumped close to the bottom of the wagon or other receptacle, and from which all of the brick will slip.

Another object of the invention is the provision of a dumping fork in which the entire 25 fork frame is pivoted closely adjacent to its upper end, permitting the rotation of the entire fork frame and the rigid fingers carried thereby throughout a large arc, thereby enabling the fork to carry out and achieve the 30 important objects above mentioned.

Another feature of the invention resides in the provision of a simple tripping mechanism or latch, which may be readily unlatched to permit tilting or swinging of the brick fork, and which may be automatically reengaged in latching position by simply dropping the 35 bottom of the fork against the edge of a wagon, on to the ground, or against any other support, whereupon the latch or latches will be automatically moved into holding position and the fork will be in readiness to handle a subsequent load.

Another feature of the invention resides in 40 providing means to limit the rocking action of the trip or latch members, said means being adjustable so that said latch members may be positioned to automatically reengage the cooperating latch portions of the brick fork.

50 Further features and objects of the invention

reside in the particular construction and arrangement of my novel fork.

The above and other objects and features of the invention, combinations of parts, details, and advantages, will be hereinafter more 55 fully pointed out, described and claimed.

Referring now to the drawings, illustrating a preferred embodiment of the present invention,

Fig. 1 is a front elevation of my novel fork; 60
Fig. 2 is a side elevation thereof;

Fig. 3 is a vertical sectional view on the line 3—3 of Fig. 1;

Fig. 4 is a cross sectional view on the line 4—4 of Fig. 2; 65
Fig. 5 is a fragmentary rear elevation of

the fork; and
Fig. 6 is a fragmentary sectional view of 70

the latching mechanism.

Referring now to the drawings, for a particular description of the invention, its construction, and operation, 1 designates lifting eyes attached to a turnable frame 2, the portion 3 being rotatable on said turntable in the usual manner. 75

Depending from the portion 2 are a pair of T-bars 4 to which are attached yokes 5, which yokes in turn are secured to beams 6, said beams having depending yoked portions 7 at their rear, in each of which is mounted 80 a pivot pin 8. The top frames 9 of the fork are pivoted on the pivot pins 8, said frames supporting, by means of vertical braces 10 and inclined braces 11, a finger bar 12 in which are mounted a plurality of vertically 85 movable but non-swingable fingers 13. The front ends of the frames 9 are yoked, as at 14, and uniting said front ends is a tie-rod 15 having reduced ends 16 which serve as 90 cooperating latch members. A shaft 17 unites the front yoked ends 18 of the beams 6, and fixed to said shaft by pins 19 are latches 20, said latches being located in the 95 yoked ends of the beams 6 and depending into the yoked ends of the fork frames 9. The lever 21 is fixed to a member 22 which is in turn fixed to the shaft 17 by a set screw 23, and one end of a lifting or tripping cable 24 is fixed to the free end of the lever 21. This cable 24 extends upwardly through the turn- 100

table portion of the device to any suitable point of operation.

Each of the fingers 13 is fixed to a hollow casting 25 by means of bolts 26, or the like, and in said casting are mounted a plurality of rollers 27 spaced to receive therebetween a tubular sleeve 28, said sleeve being provided with slots 29 in which ride a shaft 30. This shaft 30 is fixed in the casting 25, as will be clearly apparent at a glance at Fig. 2. The tubular sleeve 28 is fixed to the finger bar 12 by bolts 31 and nuts 32, said bolts passing through the flange 33 of said member 28.

Mounted on the shaft 30 is a vertical rod 34 projecting upwardly through the tubular sleeve 28 and through an aperture 35 in the finger bar 12, said rod 34 having a cup 36 slidably mounted thereon and within which is seated one end of a coiled spring 37, the other end of said spring being seated on top of the finger bar 12. Lock nuts 38 serve to keep the cup 36 at the point desired for a predetermined tension of the spring 37.

The construction of each of the fingers 13 and their connection to the finger bar 12 is identical, so that a description of one will serve as a description for all.

Fixed to each casting 25 by bolts 39 is a brick alining member 40, the front edge of this member 40 being alined with the front end 41 of the casting 25 and the shoulder 42 of the finger 13, thus providing a vertical alining member for the brick carried on the fingers 13, and insuring against disalinement of the bottom row or rows of brick when the fork is pushed into a stack of brick.

It will thus be understood by those skilled in the art that the rows or courses of brick in a kiln shrink unevenly and, therefore, vary in their horizontal alinement. Not only does each course of brick shrink in a somewhat different manner from those adjacent to it, when burned, but such variation is apt to be distorted throughout a plurality of courses. Therefore, the rows of brick in a kiln, after the kiln is burned, are in a wavelike formation, the rows or courses appearing in undulating lines of varying extent, but mostly distorted from a horizontal plane. Because of this fact, I utilize the individual vertically adjustable fingers illustrated in the present application.

I also provide each of the fingers 13 with a tapered forward end 43, so that as the device is applied to a stack of brick and forced inwardly, each finger 13 will, independently of each other, follow the line of the course of brick to which it is applied. It will be appreciated that burned brick in a kiln are in spaced or hacked relation and, therefore, the tapered forward end 43 of each finger will enable the fingers to be forced into the interstices between the brick, following the lines of least resistance and permitting the finger to assume a higher and lower vertical posi-

tion to enable it to be thus forced into the mass of brick in the kiln.

When the fork is in place, preferably under a considerable plurality of rows of brick, in order to remove the unit of brick over the fingers 13, the fork is then lifted, through the medium of the lifting rings 1, and all the brick engaging fingers 13 which were disaligned during the process of applying the fork to the brick stack, will settle down against the tension of the springs 37, and thus the entire mass or unit of brick will be simultaneously straightened, realined, and will settle into a horizontal plane at the bottom portion. The unit or stack of brick thus carried by the fork will be in a position and readiness to be dumped into a car, wagon, or other receptacle or conveyance.

During the vertical movement of the fingers 13, the castings 25 will be permitted a free vertical reciprocation by means of the rollers 27 engaging the sleeve 28, and thus reducing the friction occasioned by the reciprocation of the castings or carriages 25 on the sleeves 28.

When the fork, and the load of brick carried thereby, have been moved or conveyed to a position over a car or wagon into which the load or stack of brick is to be dumped, the fork may be lowered until it is substantially in contact with the surface of the said car or wagon. Thereupon a pull is exerted on the cable 24, raising the lever 21 and rotating the shaft 17, and hence the latch members 20 carried thereby. This will cause the latch members 20 to disengage the fixed latch members 16, whereupon the weight of the brick carried by the fingers 13 will swing the entire fork on the pivot pins 8, lowering the front ends of the fingers 13 and dumping the forward end of the stack of brick carried by said fork. Thereupon, on a lift being imparted to the rings or eyes 1, the entire fork will be raised, continuing to swing on the pivot pins 8, and withdrawing the fork from the wagon or car, at the same time permitting the balance of the stack of brick to slide gently therefrom and be deposited on the car or wagon.

After the fork is free of the stack of brick, it may be reset in lifting position by simply lowering the same against the side of the wagon, or against the ground, whereupon the inclined edge 44 of the latch members 20 will engage the fixed latch members 16, and will be forced outwardly until latching position is reached, whereupon the latch members 20 will drop into the latching position illustrated in full lines in Fig. 6. Each latch member 20 is provided with a lug 45, and an adjusting screw 46 is provided in each beam 6, to determine the limit of swing of the latch members 20 in a counter-clockwise direction. The screws 46 will be adjusted so that when the fork is dropped to reset the latch mem-

bers, the inclined face 44 will always engage the fixed latch members 16 as above described.

By having the entire fork pivoted adjacent to its upper end, but below the latching point, 5 all of the brick are allowed to slide off of the fingers 13, said pivoting also allowing the fork to be dumped quite close to the car or wagon to be loaded.

During transporting of a load or stack of 10 brick on the fork, there is no danger of the latch members 20 being released, the weight of the stack of brick on the fingers obviating this difficulty, and eliminating the necessity of using springs or other devices to hold the 15 latch members 20 in position.

I believe that the brick dumping fork illustrated and described in the present application is novel, and I have therefore claimed the same broadly herein.

20 While I have necessarily described my present invention somewhat in detail, it will be appreciated that I may vary the size, shape and arrangement of parts within reasonably wide limits, without departing from 25 the spirit of the invention.

My invention is further described and defined in the form of claims as follows:

1. A brick handling fork comprising a frame, and a plurality of fingers carried by 30 said frame, said frame being pivoted adjacent to its top rear end.

2. A brick handling fork comprising a frame, a plurality of fingers carried by said frame, said frame being pivoted adjacent to 35 its top rear end, and means engaging said frame adjacent to its top front end to normally prevent swinging of said fork on its pivot.

3. A brick handling device of the kind described, comprising a support, pivot pins carried by said support, a fork swingably mounted on said pivot pins adjacent to the upper end of said fork, a shaft carried by 45 said support, a latch fixed to each end of said shaft, fixed members on said fork adapted to be normally engaged by said latches to hold said fork in brick handling position, a lever on said shaft intermediate said latches, and means to actuate said lever to rotate said 50 shaft, whereby said latches will be moved out of engagement with said fixed members.

4. A brick handling device of the kind described, comprising a support, pivot pins carried by said support, a fork swingably 55 mounted on said pivot pins adjacent to the upper end of said fork, a shaft carried by said support, a latch fixed to said shaft, a member on said fork adapted to be normally engaged by said latch to hold said fork in brick handling position, a lever on said 60 shaft, means to actuate said lever to rotate said shaft, whereby said latch will be moved out of engagement with said fixed member, 65 and a manually adjustable stop screw adapt-

ed to be engaged by said latch to limit the movement of said latch in one direction.

5. A brick handling device of the kind described, comprising a support, pivot pins carried by said support, a fork swingably 70 mounted on said pivot pins adjacent to the upper end of said fork, a shaft carried by said support, a latch fixed to said shaft, a member on said fork adapted to be normally engaged by said latch to hold said fork in 75 brick handling position, a lever on said shaft, means to actuate said lever to rotate said shaft, whereby said latch will be moved out of engagement with said fixed member, and adjustable means to limit the movement of 80 said latch in one direction.

6. A brick handling device of the kind described, comprising a support, a fork, co-operating latching means on said support and the upper forward end of said fork, and depending members on said support, said 85 fork being pivoted on said depending members below the latching point.

In testimony whereof, I have signed my name to this specification.

WILLIAM J. SULLIVAN.
